UNITED STATES PATENT OFFICE

EDWIN A. LEE, OF PHILADELPHIA, PENNSYLVANIA

FOLDING CONTAINER

Application filed September 6, 1929. Serial No. 390,706.

My invention relates to a new and useful folding container, particularly adapted for holding, transporting and displaying delicate fabrics or articles, such as stockings, 5 scarfs or the like, in a neat folded condition, while such articles are being shipped or while such articles are on display.

My invention further relates to a novel folding container of this character, one flap 10 or wall of which is made in the form of a business reply card, the postage on the return of which is paid by the sender upon the return of said card, thereby encouraging and facilitating the mail order business and 15 avoiding the payment of postage on cards which are not ultimately used or returned to the sender.

My invention still further relates to a novel folding container of this general character which is provided with means for locking the same to prevent the accidental or unintended, opening of said container when in 20 transit or storage.

My invention still further relates to a novel folding container, whereby the character, 25 texture, color and quality of the goods may be palpably or visually ascertained from the exterior of the container and without unfolding or opening said container.

To the above ends, my invention consists 30 of a novel folding container formed of a blank having a body portion, relatively long end flaps adapted to fold over said body portion, tabs on the end of one of said flaps, side flaps adapted to fold over said body and having 35 slots therein adapted to engage said tabs when said blank is folded, the other of said end flaps having a portion thereof formed into a business reply return postal card, and 40 an extension on one of said side flaps forming a memorandum of the transaction.

My invention further consists of various 45 novel features of construction and advantage, all as hereinafter described and claimed.

For the purpose of illustrating my invention I have shown in the accompanying drawings one form thereof which is at present preferred by me, since the same has been 50 found in practice to give satisfactory and re-

liable results, although it is to be understood that the various instrumentalities of which my invention consists can be variously arranged and organized and that my invention is not limited to the precise arrangement and organization of the instrumentalities as herein shown and described. 55

Referring to the drawings:—

Figure 1, represents a plan view of a novel blank from which my folding container is 60 formed.

Figure 2, represents a plan view showing the manner of folding the blank shown in Fig. 1 to form my novel container.

Figure 3, represents a plan view similar 65 to Fig. 2 further illustrating the manner of folding the blank, shown in Fig. 1.

Figure 4, represents a view showing my novel folding container which is provided by 70 completely folding the blank shown in Fig. 1.

Referring to the drawings, in which like reference characters indicate like parts, 1 designates a blank from which my novel folding container is formed, and which comprises the body portion 2 having the side flaps 75 3 and 4 which are adapted to fold over the body portion 2 along the creases or scorings 5. The flap 4 is slightly wider than the flap 3 and is provided with the extension 6 which is foldable over said flap along the crease or 80 scoring 7 as will be understood from Fig. 2. The extension 6 bears on its outer surface the necessary information 8 which constitutes a record of the purchasers name and address and the classes of goods purchased so that 85 the seller may again approach said customer by direct mail advertising. The body portion 2 is also provided with the end flaps 9 and 10, which are adapted to fold inwardly over the body portion 2 along the creases or 90 scorings 11 and 12, as will be understood from Fig. 3. The end flap 10 is divided into a postal business reply card 13 and a strip 14, separated from the card 13 by the crease 15 along which said strip and said card may 95 be detached, from each other. The card 13 bears on one face thereof an order blank 16 which is filled in by the purchaser, and on the other face thereof, is printed the address to which the card is to be mailed as at 17. The 100

card 13 is provided with a permit number and needs no stamps, the postage being paid by the sender of the card after the card is returned to him by the purchaser, thus reducing the payment of postage to cards actually returned by purchasers which usually carry an order involving profit. The strip 14 adjacent the card 13 carries the necessary instructions 18 for detaching and mailing the card 13 to encourage and facilitate mail order business. The end flap 9 is provided with tabs 19 which engage slots 20 when the blank is in folded condition, as will be understood from Figs. 3 and 4. The body portion 2 is provided with a suitable slot 21 through which the color, quality, texture and character of the goods in the container may be ascertained without unfolding or opening the container, said slot if desired having the contour of the goods vended as for example hosiery in the present instance. If desired a transparent cover sheet may be placed over the slot 21 to protect the goods in the container from manipulation by customers and from dust and dirt, the use of said cover sheet being optional.

In folding my container, after a pair of stockings or the like has been placed on the body portion 2, the post card 13 and strip 14 are first folded inwardly along the crease 12. The narrow side flap 3 is then folded inwardly along the adjacent scoring 5 and the wide flap 4 with the extension 6 folded inwardly thereon along the scoring 7, is then folded over the body portion 2, post card 13 and strip 14 and narrow side flap 3, along the adjacent scoring 5, whereupon the end flap 9 is folded inwardly along the scoring 11 and the tabs 19 are engaged by the slots 20 to maintain the container folded and closed as will be understood from Fig. 4. It is to be understood that the tabs 19 may be provided with tongues or catches (not shown) to prevent their accidental disengagement from the slots 20 and that any number of tabs 19 and slots 20 located at any suitable point may be used.

It will thus be seen that I have devised a novel folding container which is securely closed, which permits the inspection of the goods contained therein, from without, and which includes a business reply postal card the postage upon which is payable by the original sender of the card or the seller of the merchandise, whereby mail order business is greatly facilitated and encouraged.

I am aware that the invention may be embodied in other specific forms without departing from the spirit or essential attributes thereof, and I therefore desire the present embodiment to be considered in all respect as illustrative and not restrictive, reference being had to the appended claims rather than to the foregoing description to indicate the scope of the invention.

Having thus described my invention, what I claim as new and desire to secure by Letters Patent is:—

1. A blank of the character stated for forming a folding container, comprising a body portion having a slot therein, a relatively narrow side flap for, and foldable inwardly over, said body portion, an opposite relatively wide side flap for, and foldable inwardly over, said body portion, an end extension on one end of, and foldable inwardly over, said wide side flap, an end flap for, and foldable inwardly over, said body portion, said end flap comprising a detachable business reply card, an opposite end flap for and foldable inwardly over said body portion and a plurality of tabs on the free end of said end flap, there being juxtaposed slots in said side flaps, adapted to engage said tabs, when said blank is in folded condition. 70

2. A blank of the character stated for forming a folding container, comprising a body portion having an inspection slot therein, a relatively narrow side flap for, and foldable inwardly over, said body portion, an opposite, relatively wide side flap for, and foldable inwardly over, said body portion, a detachable extension on one end of, and inwardly foldable over said wide side flap, a relatively short end flap for and foldable inwardly over said body portion, said end flap comprising a detachable business reply card and an adjacent instruction non-detachable strip, a relatively long opposite end flap for, and foldable inwardly over, said body portion, and a plurality of tabs on the end of said end flap, there being juxtaposed slots in the ends of said side flaps adapted to engage said tabs when said blank is in folded condition. 85

3. A folding container of the character stated, comprising a body portion, a relatively short end flap forming a detachable business reply card, folded inwardly over said body portion, a relatively narrow side flap having a slot therein and folded inwardly over said body portion and said card, an opposite relatively wide slotted side flap having a foldable end extension, and folded over said body portion, said card and said narrow side flap, and a relatively long end flap folded over said body portion, card and side flaps, and tabs on the end of said long end flap adapted to engage the slots in said side flaps to retain said container in the closed folded condition. 100
